Primary Examiner — Brandon M Rosati*Assistant Examiner* — Marissa J Cash(74) *Attorney, Agent, or Firm* — Banner & Witcoff, Ltd.(57) **CLAIM**

The ornamental design for a flying vehicle and/or toy replica thereof, as shown and described.

DESCRIPTION

FIG. 1 is a perspective view of a flying vehicle and/or toy replica thereof showing our new design;

FIG. 2 is a left side view thereof;

FIG. 3 is a right side view thereof;

FIG. 4 is a front view thereof;

FIG. 5 is a rear view thereof;

FIG. 6 is a top plan view thereof; and,

FIG. 7 is a bottom view thereof.

The broken line showing of features of the flying vehicle and/or toy replica is for illustrative purposes only and forms no part of the claimed design.
